Inventor:

Frederick A. Stevens
By Horatio E. Bissell

Attorney:

UNITED STATES PATENT OFFICE.

FREDERICK A. STEVENS, OF PROVIDENCE, RHODE ISLAND.

LENS-POST SLEEVE AND METHOD OF FORMING THE SAME.

1,267,472.

Specification of Letters Patent. Patented May 28, 1918.

Application filed February 14, 1918. Serial No. 217,071.

To all whom it may concern:

Be it known that I, FREDERICK A. STEVENS, a citizen of the United States, residing at Providence, in the county of Providence

5 and State of Rhode Island, have invented certain new and useful Improvements in Lens-Post Sleeves and Methods of Forming the Same, of which the following is a specification.

10 My invention relates to the means for attaching the lenses to the posts or screws of eyeglass and spectacle mountings.

It has heretofore been unsuccessfully attempted to apply the cementitious material in such a manner that the resultant sleeve shall at all points thoroughly fill the spaces between the attaching posts and lenses.

15 The essential objects of my invention are to effectively convey and introduce the filling or cementitious material into these spaces; and to produce a sleeve adapted to fill spaces of varying dimensions.

20 To the above ends essentially my invention consists in such parts and combinations of parts, and in such steps and successions of steps as fall within the scope of the appended claims.

25 In the accompanying drawings which form a part of this specification,

Figure 1 is a plan view of a lens and its adjacent parts, embodying my invention,

30 Figs. 2 and 3, a side elevation and transverse section respectively of a spiral metallic core,

Figs. 4 and 5, a like elevation and section respectively of the same coated,

35 Fig. 6, a longitudinal central section of an end portion of the lens and adjacent mounting parts, showing in vertical central section a cementitious bearing sleeve in its initial stage of insertion,

Fig. 7, a similar section showing the sleeve after complete insertion,

40 Figs. 8 and 9, a side elevation and transverse section respectively of a braided fiber core,

Figs. 10 and 11, a similar elevation and section respectively of the same coated,

45 Fig. 12, a section corresponding to that of Fig. 7 showing the fiber cored sleeve in final position, and

Fig. 13, a section of a double strap lens

mounting in connection with which my invention is capable of use.

55 Like reference characters indicate like parts throughout the views.

My invention in its preferred form of embodiment is shown in conjunction with a spectacle lens 15, bridge 16, and a portion 60 of the temple 17 pivoted to the end piece 18 by the pin 19. The lens mountings carried by both the bridge 16 and end piece 18 are identical in form, and each comprises a lens clamp 20 and 21, carrying fast there- 65 in or integral therewith the attaching post 23 having an end thread 24 to engage the thread 25 of a clamping nut 26.

If desired the lens mountings may be of the form shown in Fig. 13, wherein a second strap 28 provided with a threaded perforation 29 is substituted for the nut 26; and a post 30, slidable in a perforation 31 in the strap 21, is substituted for the originally fixed post 23.

70 The lens near each end is provided with a hole 32 to receive the post 23, which hole is sufficiently ample to form a space 34 around the post.

75 In preparation for filling this space a compressible metallic core 36 of suitable length consisting of spiral loops 37, as shown in Fig. 2, has applied thereto a coating 38 of shellac or other cementitious material in such quantity as to fill the interstices 39 between the coils, and form a tubular length such as is shown in Figs. 4 and 5. This member is severed into tubes or tubular sections 40 of a length slightly greater than the thickness of the lens, and is manually inserted into the space 34 where it abuts against the strap 21 and loosely surrounds the post 23, with one of its ends projecting beyond the face of the lens, as shown in Fig. 6.

90 Heat is next applied by a flame or otherwise to the parts adjacent the sleeve or tube 40 which softens the coating thereon, and while in this softened state the nut 26 is tightened longitudinally crushing the tube 100 and thereby combining with the core to radially distribute the coating material throughout the entire area of the space 34, as shown in Fig. 7.

95 An acceptable form of conveyer for the cement, may if preferred, consist of a tubu-

lar core 42 of fibrous material, preferably of braided fiber, whose textural interstices are not shown, since they are invisible, but common to textile fabrics. Such a core is shown in Figs. 8 and 9. The coating 43 which covers the surface and interstices of this core is shown in Figs. 10 and 11. A finally inserted section or sleeve 45 cut from this length is shown in Fig. 12.

10 When a sleeve is inserted in the double strap structure shown in Fig. 13, the second strap 28 is manually pressed against the end of the sleeve, and the screw 30 is then engaged in the opening 29.

15 It will be noted that the cores 36 and 42 serve as conveyers of the cementitious material to the holes where the latter is to be applied; that after location in the holes the cores insure an even distribution of the material, and that the compressibility of the cores squeezes the material from their interstices and radially spreads the same.

I claim:—

1. The method of uniting a lens and post consisting in longitudinally compressing under a temperature sufficient to soften a

coating a core located between the lens and the post and provided with a cementitious coating.

2. The method of uniting a lens and post 30 consisting in surrounding the post within the lens with a compressible tubular core carrying a coating of cementitious material, applying heat to soften the coating, and longitudinally compressing the core to expel 35 and spread the softened coating.

3. The method of uniting a lens and post consisting in placing loosely around the post within the lens a core saturated with cementitious material, and then longitudinally 40 compressing the core to expel said material against the post and lens.

4. As a new article of manufacture a lens-post sleeve comprising a tubular compressible core, and a cementitious coating impregnating and covering the same.

5. As a new article of manufacture a lens-post sleeve comprising a spiral core, and cementitious coating incorporated in the core.

In testimony whereof I have affixed my 50 signature.

FREDERICK A. STEVENS.
